CARTON FOR PACKAGING MERCANDISE IN MULTIPLE

Richard C. Poole, Jr., New Rochelle, N. Y., assignor to Walton D. Lynch, trustee, Hamden, Conn.

Application November 1, 1954, Serial No. 465,904

6 Claims. (Cl. 206—65)

This invention relates to improvements in cartons for the packaging of a plurality of articles as a unit. The invention has particular application to cartons for the packaging of cylindrical articles, such as glasses, jars or cans, for example cans containing food, beverages, oil or dry products.

Packaging of several articles of merchandise as a unit has been widely adopted, since the multiple package or unit can be readily carried by the consumer without further wrapping or packaging and since packaging in multiple facilitates storage and handling of the merchandise in transport, storage and sale.

Special considerations enter into the design and the manufacture of cartons and carrier cartons for cans which are not present in other form of carriers, for example, the commonly known bottle carriers.

Can packages or carriers are single-use items. They are discarded after the cans are removed from the package and are not re-used.

For this reason, the cost of the carton is a very important factor, since the entire cost must be absorbed in the single trip which the carton makes from the manufacturer to the consumer, in distinction from bottle carriers which usually make several round trips, reducing the cost of the carrier per sale proportionately.

In single-use cartons savings in blank size and board caliper are of particular importance and it is desirable to maintain board area and board caliper at a minimum.

Reduction of the blank size and of the board caliper generally leads to a corresponding loss of strength of the carton. One of the structural details which imparts strength to cartons of the aforementioned character, particularly can carriers, is a center partition between the two rows of cans or other articles. One of the principal functions of a center partition is to transmit a portion of the load of the carton contents to the top wall or handle by which the carton is carried.

Center partitions of conventional form require additional board, and there has been a tendency to eliminate them in order to reduce the size of the blank. Elimination of the central load carrying structure which connects the bottom of the carton and the top, puts the entire load of the carton contents on the outer sidewalls. This is undesirable, particularly in forms of the carton or carrier in which the cans are locked in the carton by slots or apertures in the sidewalls through which the ends of the cans partially project. These apertures lie at, or adjacent to, the fold lines along which the sidewalls of the carton are articulated to the top wall structure and the bottom wall structure of the carton, respectively, and reduce the load transmitting portion of the board to considerably less than the width of the sidewalls.

2

The invention, among other improvements and advantages, provides an improved carton construction by means of which a load carrying center partition is formed in a carton of the above mentioned type without the need for additional board. The invention thus permits construction of a carton or carrier from a blank which is no larger than a blank for a carton having no central partition.

The central partition structure provided by the invention in its preferred form is articulated to the bottom structure and is secured to the top structure either by gluing, stitching, stapling or riveting either to the underside or the top side of the top structure or between overlapping portions of the top panels, as the case may be.

The provision of the central partition permits even greater economy, since it permits reduction of the board caliper due to the fact that the outer sidewalls are not subjected to the entire load of the carton contents, but only to a portion of the load, the remainder of the load being transmitted directly to the top wall structure and the handle, in the event a handle is provided.

The center partition provided by the invention further increases the strength and the rigidity of the carton since it prevents sagging of the bottom and bellying out of the top, if the carton is lifted up by the top panel structure.

These and other features, objects, and advantages of the invention will appear more fully from the detailed description which follows, accompanied by drawings showing, for the purpose of illustration, a preferred embodiment of the invention. The invention also consists in certain new and original features of construction and combination of structural elements hereinafter set forth and claimed.

Although the characteristic features of the invention which are believed to be novel will be particularly pointed out in the claims, the invention itself and the manner in which it may be carried out may be better understood by referring to the following description taken in connection with the accompanying drawings forming a part of it, in which:

Fig. 1 is a plan view of a flat blank from which a carrier carton embodying the present invention may be made;

Fig. 2 is a perspective view of the blank after an initial folding operation;

Fig. 3 is a perspective view of the blank of Fig. 2 loaded with cans;

Fig. 4 is a perspective view of the blank and cans after a further folding operation;

Fig. 5 is a perspective view of the completed sealed carrier carton of Figs. 1 to 4;

Fig. 6 is a plan view of a modified form of blank including a handle;

Fig. 7 is a perspective view of a carrier carton made from the blank of Fig. 6, loaded with cans and sealed;

Fig. 8 is an end view of the carrier of Fig. 7. In the following description and in the claims various details will be identified by specific names for convenience. The names, however, are intended to be as generic in their application as the art will permit. Corresponding reference characters identify corresponding parts in the several figures of the drawings.

In the drawings accompanying, and forming part of, this specification, certain specific disclosure of the invention is made for the purpose of explanation of broader

aspects of the invention, but it is understood that the details may be modified in various respects without departure from the broad principles of the invention and that the invention may be applied to other structures than the ones specifically shown in the drawings.

The blank A shown in Figure 1 may be cut and scored, in multiple, from large rolls or sheets of sheet material, more particularly foldable sheet material, such as paper board, on automatic cutting and scoring machines. Only one surface of the stock requires imprinting or decorative finishing, since only one side appears as the outside of the carrier or carton. The blank A is shown with its unfinished back side facing the observer.

The several constituent parts of the blank are set apart by fold or crease lines or by cuts. The blank comprises a bottom structure consisting of a single bottom panel 11 to which sidewall panels 12 and 13 are articulated along bottom fold lines 14 and 15. Top panels 16 and 17 are articulated to the sidewall panels 12 and 13 along top fold lines 18 and 19, respectively.

Cartons or carriers embodying the present invention may be provided with any one of various conventional means for locking the merchandise in the assembled carton or carrier. Such means are illustrated, for example, in the patent to Carruth, No. 2,656,960, but in the illustrated example, they comprise a plurality of arcuate cuts 20 at, or adjacent, the bottom and top fold lines 14, 15, 18 and 19. These arcuate cuts provide self opening apertures into which portions of the ends of the cans, glasses, jars, or other articles project, when the carton is assembled.

A partition-forming central structure of the carton comprises strips 21 and 22 cut from the stock of the bottom panel 11 and from the sidewall panels 12 and 13, respectively. In their preferred form the strips 21 and 22 have flared out enlarged base portions 23 and 24 along which the strips are articulated to the bottom panel 11 at base fold lines 25 and 26 which, due to the flared design, are longer than the width w of the strips. The strips 21 and 22 are staggered with respect to the arcuate cuts which define the areas of the bottom 11 and top structure 16, 17 against which the can ends rest.

The other ends 27 and 28 of the strips are also enlarged and are, in the illustrated embodiment, of circular shape comprising finger holes 29 and 30. The purpose of these finger holes will become apparent as the description proceeds.

The top panels 16 and 17 are provided with similar finger holes or cutouts 31 and 32, respectively. Crease lines 33, 34 may extend across the enlarged top ends 27 and 28 of the strips.

The assembly of the blank A into carton or carrier form and its loading with merchandise may proceed as follows:

For the purpose of assembly and loading, the flat blank A may be advanced in a transverse direction, as indicated by the arrow 35 in Figure 2. This may be done by placing the carrier on the conveyor of suitable folding and filling machinery. As the blank advances, the strips 21 and 22 are raised to a vertical position.

Next, a plurality of cans or other articles to be packaged are deposited on the blank A as shown in Figure 3. The cans 36 are arranged in two rows, one row being on one side of the strips 21, 22 and the other row being on the other side. As is apparent from Figure 3, the width of the two rows of cans, in other words twice the can diameter, is slightly greater than the width of the bottom panel 11, as measured between the bottom fold lines 14 and 15. For this reason the can chimes 37 substantially register with the arcuate cuts 20 and protrude slightly through the sidewalls 12 and 13 when the sidewalls are folded into upright position.

Figure 4 illustrates the blank A and the cans 36 at a further advanced stage of the operations. The sidewall 13 is upright and the top wall 17 is folded over

the tops of the cans. The enlarged top ends of the strips 27 and 28 to which adhesive a was previously applied (see Figure 2) are folded over, and into adhesive engagement with, the top panel 17. In this position the finger holes 29 and 30 of the strips register with the cutouts 32 in the top panel 17.

The sidewall 12 is then folded upright and the top panel 16 is folded over the tops of the cans and brought into adhesive engagement with the top panel 17 and the ends 27, 28 of the strips. For this purpose adhesive a was previously applied to a marginal portion of the panel 16, as shown in Figure 4.

Figure 5 shows the loaded and closed carrier A'. As is apparent from Figure 5, the finger holes 31 in the top panel 16 register with the finger holes 29 and 30 in the ends 27, 28 of the strips. Thus finger grip apertures are provided in the top structure of the carrier through which two fingers may be inserted for the purpose of lifting and carrying the filled carton. Due to the construction of the carrier three plies of stock are present at the finger-grip apertures of the carrier.

The strips 21 and 22 form a central partition between the two rows of cans and transmit a portion of the weight of the cans directly from the central portion of the bottom panel 11 to the points at which the carrier is lifted up. In this manner sagging of the bottom panel and bellying out of the top structure is prevented.

It is also readily seen that the load sustained by the sidewalls is reduced. This is of importance, since the lines of articulation between the top and bottom structure and the sidewalls, respectively, are interrupted and are relatively short. As seen in Figure 4, for example, the fold lines 15 along which the sidewall panel 13 remains attached to the bottom panel 11 are relatively short and are interrupted by the arcuate cuts 20.

The carrier A' is sturdy and requires no more stock than conventional carriers having no central partition.

Figure 6 illustrates a blank B, corresponding in most particulars to the blank A shown in Figure 1, except for the provision of handle panels 38 and 39 articulated to the top panels 16 and 17 along handle fold lines 40 and 41. The handle panels are provided with hand apertures 42 and 43. The strips 21 and 22 are again shown as having flared base portions 23 and 24, but their top ends 27' and 28' are plain. In all other respects the blank B corresponds with the blank A and the same reference numerals are applied to corresponding elements. Figures 7 and 8 show a closed and loaded carrier B' assembled from the blank B. The handle panels 38 and 39 lie face to face. The hand apertures 42 and 43 coincide, and the ends of the strips 21 and 22 extend between the handle panels and are secured thereto in a suitable manner. Wire staples 44 are particularly suitable for securing handle panels and central partition, since they obviate the use of adhesive in the assembly of the carrier.

Obviously the invention may be applied to carriers and cartons in which the merchandise are held or locked by other means than the ones specifically disclosed herein.

What is claimed is:

1. A package of chime-end tin cans, the package comprising, a plurality of chime-end tin cans, arranged in two opposite and parallel rows containing equal numbers of cans, and an enclosing carton, the carton comprising, a one-piece bottom panel having can end-supporting areas thereon equal in number to the number of cans; two side wall panels articulated to said bottom panel along bottom fold lines spaced less than twice the diameter of the chime ends; a top structure including two top panels articulated to the tops of said side wall panels along top fold lines, said two top panels being secured together, the spacing of the top fold lines being equal to the spacing of the bottom fold lines; and a central structure comprising at least one strip cut from the stock of the bottom panel and of a side wall panel by a substantially U-shaped cut, the bight of the U lying in the side wall panel below the

top fold line, said strip being staggered with regard to said areas and being integral with, and articulated at one end to, said bottom panel along a base fold line intermediate said bottom fold lines, from which base fold line said strip extends at right angles with respect to said bottom panel, the other end of the strip being secured to said top panel structure; said side wall panels having chime apertures therein immediately adjacent said bottom and said top fold lines through which apertures the chimes of cans resting on said bottom may partially project, said apertures being staggered with regard to said strip and being in line with said areas.

2. A package of chime-end tin cans, the package comprising, a plurality of chime-end tin cans, arranged in two opposite and parallel rows containing equal numbers of cans, and an enclosing carton, the carton comprising, a one-piece bottom panel having can end-supporting areas thereon equal in number to the number of cans, two side wall panels articulated to said bottom panel along bottom fold lines spaced less than twice the diameter of the chime ends; a top structure including two top panels articulated to the tops of the said side wall panels along top fold lines, said two top panels being secured together, the spacing of the top fold lines being equal to the spacing of the bottom fold lines; and a central structure comprising one strip cut from the stock of the bottom panel and of one of said side wall panels, and a second strip cut from the stock of the bottom panel and of the other side wall panel, said strips being formed by substantially U-shaped cuts, the bight of the U lying in the side wall panel below the top fold line, said strips being staggered with regard to said areas and being integral with, and articulated at one end to, said bottom panel along base fold lines intermediate said bottom fold lines from which base fold lines said strips extend at right angles with respect to said bottom panel, the other ends of the strips being secured to said top panel structure, said top panel structure having at least one finger grip aperture therein, said side wall panels having chime apertures therein immediately adjacent said bottom and said top fold lines through which apertures the chimes of cans resting on the bottom panel may partially project, said apertures being staggered with regard to said strips and being in line with said areas.

3. A package of chime-end tin cans, the package comprising, a plurality of chime-end tin cans, arranged in two parallel and opposite rows containing equal numbers of cans, and an enclosing carton, the carton comprising, a one-piece bottom panel having can end-supporting areas thereon equal in number to the number of cans; two side wall panels articulated to said bottom panel along bottom fold lines spaced less than twice the diameter of the chime ends; a top structure articulated to the tops of said side wall panels along top fold lines, the spacing of the top fold lines being equal to the spacing of the bottom fold lines; and a central structure comprising at least one strip cut from the stock of the bottom panel and of a side wall panel by a substantially U-shaped cut, the bight of the U lying in the side wall panel below the top fold line, said strip being staggered with regard to said areas and being integral with, and articulated at one end to, said bottom panel along a base fold line intermediate said bottom fold lines from which base fold line said strip extends at right angles with respect to said bottom panel, the other end of the strip having an aperture therethrough and being secured to said top structure, said top structure having a finger grip aperture extending through it in register with the aperture in said strip, said side wall panels having chime apertures therein immediately adjacent said bottom and said top fold lines through which apertures the chimes of cans resting on the bottom panel may partially project, said apertures being staggered with regard to said strip and being in line with said areas.

4. A package of chime-end tin cans, the package comprising, a plurality of chime-end tin cans, arranged in two parallel and opposite rows containing equal numbers of

cans, and an enclosing carton, the carton comprising, a one-piece bottom panel having can end-supporting areas thereon equal in number to the number of cans; two side wall panels articulated to said bottom panel along bottom fold lines spaced less than twice the diameter of the chime ends; a top structure articulated to the tops of said side wall panels along top fold lines, the spacing of the top fold lines being equal to the spacing of the bottom fold lines; and a central structure comprising a strip cut from the stock of the bottom panel and one side wall panel by a substantially U-shaped cut, and another strip cut from the stock of the bottom panel and of the other side wall panel by a similar U-shaped cut, the bight of the U lying in the side wall below the top fold line, said strips being staggered with regard to said areas and being integral with, and articulated at one end to, said bottom panel along base fold lines intermediate said bottom fold lines from which base fold lines said strips extend at right angles with respect to said bottom panel, the other ends of the strips having an aperture therethrough and being secured to said top structure, said top structure having a finger grip aperture extending through it in register with the apertures in said strips, said side wall panels having chime apertures therein immediately adjacent said bottom and said top fold lines through which apertures the chimes of cans may partially project, said apertures being staggered with regard to said strips and being in line with said areas.

5. A package of chime-end tin cans, the package comprising, an even number of chime-end tin cans, arranged in pairs in double file, and an enclosing carton, the carton comprising, a one-piece bottom panel having can-supporting areas thereon equal in number to the number of cans; two side wall panels articulated to said bottom panel along bottom fold lines spaced less than twice the diameter of the chime ends; two top panels integral with, and articulated to, said side wall panels along top fold lines; and two handle panels articulated to said top panels along handle fold lines spaced from the top fold lines less than the diameter of the can ends; and a central structure comprising at least one strip cut from the stock of the bottom panel and of a side wall panel by a substantially U-shaped cut, the bight of the U lying in the side wall panel below the top fold line, said strip being staggered with regard to said areas and being integral with, and articulated at one end to, said bottom panel along a base fold line intermediate said bottom fold lines from which base fold line said strip extends at right angles with respect to the bottom panel, the other end of the strip extending between said handle panels, said strip and handle panels being secured together, said side wall panels having chime apertures therein immediately adjacent said bottom and said top fold lines through which apertures the chimes of cans resting on the bottom panel may partially project, said apertures being staggered with regard to said strip and being in line with said areas.

6. A package of chime-end tin cans, the package comprising, six chime-end tin cans, arranged in two parallel and opposite rows of three cans, and an enclosing carton, the carton comprising, a one-piece bottom panel having six can end supporting areas thereon; two side wall panels articulated to said bottom panel along bottom fold lines spaced less than twice the diameter of the chime ends; two top panels integral with, and articulated to, said side wall panels along top fold lines; and two handle panels articulated to said top panels along handle fold lines spaced from the top fold lines less than the diameter of the chime ends; and a central structure comprising one strip cut from the stock of the bottom panel and of one of the side wall panels, and a further strip cut from the stock of the bottom panel and of the other side wall panel, said strips being formed by substantially U-shaped cuts, the bight of the U lying in the side wall panel below the top fold line, said strips being staggered with regard to said areas and being integral with, and articulated at

one end to, said bottom panel along base fold lines, said base fold lines being aligned and lying internally of said bottom panel, from which base fold lines said strips extend at right angles with respect to the bottom panel, the other end of the strips extending between said handle panels and being secured thereto, said side wall panels having chime apertures therein immediately adjacent said bottom and said top fold lines through which apertures the chimes of the cans may partially project, said apertures being staggered with regard to said strips and in line with said areas.
